UNITED STATES PATENT OFFICE

NEWTON C. SCHELLINGER, OF ELKHART, INDIANA, ASSIGNOR TO CHICAGO TELEPHONE SUPPLY COMPANY, OF ELKHART, INDIANA, A CORPORATION OF DELAWARE

RHEOSTAT

Application filed October 25, 1926. Serial No. 143,906.

This invention has to do with current control devices such as rheostats and potentiometers. More particularly the present invention relates to improvements which I have made in rheostats of the same general character as that disclosed in my copending patent application, Serial No. 114,126 filed June 7th, 1926.

I have found that there is a demand for 10 a rheostat having a properly cooled resistant strip. To meet this demand I have devised a rheostat having a molded composition base provided with a corrugated outer periphery. The corrugations insure cooling of the strip, 15 which preferably encircles the corrugated periphery.

The base of my novel control device is preferably of a hollow cylindrical shape and has one end closed by a depressed or concave 20 portion. This depressed portion is integral with the wall of the base and defines a seat for the rheostat contact mechanism.

Another feature of my rheostat base is the provision of novel stops for limiting the 25 travel of the contact arm; the stops being part of the molded product or base. Also adjacent the stops the base has formed there- 30 in seats for receiving the heads of the screws employed for securing the resistant strip to the base. Each of these seats is rectangular in shape and serves to lock the associated screw against rotation.

Still another feature of the invention per- 35 tains to the construction of the resilient washer associated with the contact arm of the device. The washer comprises essentially a depressed circular piece of material provided with a concentric circular aperture for receiv- 40 ing the operating shaft of the device and hav- ing a lateral extension comprising an arm equipped with a bifurcated end.

For purposes of simplicity in construction, I have provided a slot in the molded base for receiving the bifurcated arm of the wash- 45 er; the arm being fastened to the base by one of the screws previously mentioned, thus an- choring the washer against rotation.

The resistance strip I employ in my present device may be wound with wire in accordance 50 with the features of the co-pending applica-

tion of Charles Havlish, Serial No. 729,479, filed August 1, 1924.

Other objects and advantages of my invention will more fully appear from the following detailed description taken in connection 55 with the accompanying drawings which illustrate an embodiment thereof and in which

Figure 1 is an elevation of my novel device looking at it from one side;

Fig. 2 is an elevation of the device looking 60 at it from another side;

Fig. 3 is a sectional view through the de- 65 vice illustrating the manner in which same is fastened to a mounting panel;

Fig. 4 is a fragmentary sectional view taken 65 on substantially the line 4—4 of Fig. 3 look- ing in the direction indicated by the arrow;

Fig. 5 is a detail view illustrating my novel resilient washer;

Fig. 6 is a sectional view taken on sub- 70 stantially the line 6—6 of Fig. 5;

Fig. 7 is a view taken on the line 7—7 of 75 Fig. 3 looking downwardly;

Fig. 8 is a sectional view taken on the line 8—8 of Fig. 3 looking in a direction indicated 75 by the arrow;

Fig. 9 is a fragmentary view drawn to an enlarged scale of a portion of a resistant strip embodying novel features of my in- 80 vention;

Fig. 10 is a sectional view taken on the line 10—10 of Fig. 9;

Fig. 11 is a sectional view taken on the line 11—11 of Fig. 9 drawn to an enlarged scale; 85 and

Fig. 12 is a view partly in sections taken on substantially the line 12—12 of Fig. 9 looking upwardly.

Referring now to the drawings in detail in which like reference numerals designate simi- 90 lar parts throughout the several views, 15 denotes generally a base or frame member which is preferably made of molded composi- 95 tion, such as phenolic condensation matter. I have obtained excellent results by making the base of "bakelite".

This base includes a hollow body defined by a circular wall having its outer periphery provided with a plurality of corrugations 16. At one end the base is closed by a depressed 100

or concave portion 17 lying within the dimensions of the base. This depressed portion is cup-like in shape and has a substantially flat portion 18 serving as a seat for receiving the contact mechanism of the device. Located 5 within the hollow 19 of the base 15 is a circular sleeve 20 which is preferably secured to the body at the time the same is molded in a manner well known to those familiar with the phenolic condensation molding art. This 10 sleeve 20 includes a threaded opening 21 and a reduced opening 22; an operating shaft 24 telescopes this sleeve 20 and has a reduced portion 23 extending through the reduced opening 22 in sleeve 20. Also shaft 24 has an 15 annular shoulder 25 which abuts a portion of the sleeve 20 defining the opening 22 as shown in Fig. 3. Threaded into the sleeve 20 and surrounding the shaft 24 is a thimble 27 extending through an aperture 28 in a mounting panel 30. The thimble 27 has a polygonal shaped head 29 which abuts a washer 31 surrounding the threaded portion of the thimble. This thimble 27 serves to securely clamp the 20 base 15 to the mounting panel 30. The external end 32 of shaft 24 has secured thereto a knob 33 by means of which the shaft may be turned with facility.

Mounted upon the reduced end 23 of shaft 24 is a resilient washer 35 which is illustrated 30 in detail in Figs. 5 and 6. This washer normally rests upon the seat portion 18 of the concave or depressed end 17 of the base 15. The peripheral edge of the washer is castellated or serrated as indicated at 36. Also, 35 the washer has a depressed or concave shape as is obvious in Fig. 6. Furthermore, the washer is provided with a lateral extension or arm 38 which somewhat resembles a U in 40 shape. One end of this arm (Fig. 6) is bifurcated as denoted at 39. The purpose of this forked or bifurcated end 39 will be more fully explained hereinafter.

Also mounted on the reduced end 23 of shaft 24 is a contact arm assembly 45 which 45 is most clearly shown in Figs. 1 and 3 and which is claimed in my copending patent application Serial No. 114,126, filed June 7, 1926. This assembly includes a contact arm 50 having an arcuate shaped mounting portion 47. The base or mounting portion 47 is provided with an arcuate slot 48 so as to provide the arm with requisite resiliency. The base is also provided with an offset portion 55 49 which is adapted to be flexed to the plane of the mounting of base 47 as will become more apparent hereinafter. I preferably make a contact arm and the base 47 of nickel silver in view of the electrical qualities of 60 this metal. The contact arm 46 comprises a slanting portion 51 and a substantially flat contact portion 50. Mounted on the offset portion 49 is a collar or hub 52 having a bore 53 adapted to receive the end 23 of the shaft 65 24. This collar 52 is suitably clamped to the

portion 49 which is adapted to be flexed into and out of the plane of the base 47. A set screw 56 serves to secure the collar 52 to the end 23 of the shaft. The slot 48 in the base 70 47 provides the offset portion 49 with sufficient resiliency to enable it to urge the contact arm into engagement with the resistance wire or winding of the resistant strip designated generally by the reference character 62. 75

Obviously, when the contact arm assembly 45 is mounted on the end 23 of the operating shaft abutting the resilient washer 35, the washer 35 not only serves as a resilient mounting for the assembly but also serves as a 80 universal mounting due to its arcuate and depressed shape. Such an arrangement insures a smooth movement on the part of the contact arm surrounding its entire range of movement. Then, too, it should be noted 85 that with the exception of the contact portion 50 the entire contact arm assembly 45 is disposed in the depressed portion 17 of the base 15 within the dimensions of the base thus permitting of a very compact piece of 90 electrical apparatus.

The resistant strip 60 comprises an insulator or core 61 having wound thereon a plurality of windings of resistance wire 62. This resistance 60 may be made in accordance 95 with the winding process disclosed in the copending patent application of Charles Havish, Serial No. 729,479, filed August 1, 1924, or it may be manufactured in accordance 100 with the process I shall describe in connection with the illustrations in Figs. 9 to 12 inclusive. This strip 60 encircles the corrugated periphery 16 of the base 15 and is fastened at its ends in a novel manner to be 105 described hereinafter. One edge of the strip 110 abuts the corrugated flange 64 formed integral with the base. The other or outer edge of the strip is adapted to be engaged by the contact portion 50 of arm 46. The base 15 has formed integral therewith a pair of stops 115 65 and 66 (Fig. 7) which serves to limit the travel of the contact arm 46. To the best of my knowledge I am the first to form the stops integral with the main portion of the body; both the stops and the main portion 115 of the body comprising or rather being part of the same molded product.

Now, it will be evident from Figs. 1 and 2 that the corrugations of the corrugated flange 64 align with the corrugations 16 of the body 120 15. The diameter of the corrugated flange is just enough larger than the diameter of the corrugated body 15 to enable it to accommodate the resistance strip 60 when the same is disposed about the base 15. The flange 64 125 has a slightly irregular portion 70 which cooperates with the fastening bolts used to secure the resistance strip to the base 15.

The portion of the body 15 adjacent the irregular portion 70 of the flange 64 is not 130

corrugated as is evident from Fig. 4. I have designated this uncorrugated section of the body by the reference character 71. The previously described stops 65 and 66 are formed integral with this portion 71. Now the section or portion 71 has a pair of elongated apertures 73 and 74 which communicate with apertures 75 and 76 in portion 70 of the flange (Fig. 2). The apertures or openings 73 and 75 are adapted to receive a square headed screw 77 and the apertures or openings 74 and 76 are adapted to receive a square headed screw 78. By providing the openings 75 and 76 it is possible to insert the shanks of the associated screws expediently and with facility into slots or apertures 73 and 74.

Now when the two screws or bolts 77 and 78 are in their proper position they will both be substantially parallel to the panel 30 as is obvious from Fig. 3. Screw 77 has a square head 79 and screw 78 has a square head 80 which are adapted to be locked in position within the hollow or opening 19 of the base 15. The depressed or concave portion 17 of the base has a pair of tapered or slanting surfaces 81 and 82 adapted to cooperate with the heads 79 and 80 of the previously mentioned bolts (Fig. 4). These surfaces 81 and 82 taper outwardly towards the periphery of the base 15. The tapering surface 82 is illustrated in Fig. 3 and tapering surface 81 is substantially like the surface 82. The surface 81 terminates in a pocket or seat 83 for the screw head 79 and the surface 82 terminates in a pocket or seat 84 for the screw head 80. Pocket 83 is defined by a pair of projections 85 and 86 formed integral with the depressed portion 17 of the base. On the other hand pocket 84 is defined by the projections 86 and 87 formed integral with the base. The tapered surfaces 81 and 82 permit the screw heads 79 and 80 to all times slide into their respective pockets 83 and 84 upon the insertion of the screws 77 and 78 into their respective apertures in the section 71 of the base. Also the projections 85, 86 and 87 cooperate to prevent rotation of the screws. In other words, the screws are anchored against rotation by means formed integral with the molded base 15.

The shank of screw or bolt 77 is adapted to extend through an aperture 89 at one end of the strip 61 of resistance strip 60 and the shank of screw or bolt 78 is adapted to extend through an aperture 90 in the other end of the resistance strip 61. The two bolts cooperate to securely clamp the resistance strip about the corrugated periphery of the base 15. The resistance wire 62 extends clear up to the shank of bolt 77 and has its end bent into a hook 89' which embraces the shank of the bolt. A washer 91 is disposed on top of this hooked end 89' and a pair of locknuts 92 and 93 threaded upon the external end of the

bolt 77 serves to securely clamp the associated end of the resistance strip to the base and at the same time serves to insure a good electrical connection between the resistance and the bolt 77. The bolt 77 can be connected in any desirable manner to one end of an electrical circuit.

The resistance wire 62 does not extend clear up to the shank of bolt 77 as is obvious in Fig. 4. A pair of washers 95 and 96 encircle the free end of the bolt 78 and a pair of lock-nuts 97 and 98 serve to securely clamp the washers to the associated end of the resistance 60, thus clamping the resistance to the base.

Also the bolt 78 may be connected in any desirable manner to another end of the previously mentioned electrical circuit in which the resistance is connected. Now, obviously, it is necessary in order to establish a complete circuit, to connect the bolt 78 to the contact arm or contact mechanism 45. I accomplish this connection through the means of the previously described bifurcated arm 38 on the resilient washer 35. This bifurcated end 39 of the arm 38 extends through an aperture 99 in the depressed portion 17 of the base which aperture communicates with pocket 84 associated with the head 80 of the bolt 78. The bifurcated end 39 of the arm 38 extends through this aperture 99 into the pocket 84 and straddles the shank of bolt 78. The head 80 of the bolt 78 is adapted to securely clamp this bifurcated end 39 to the associated portion of the base 15. Thus it will be apparent that the arm 38 of the washer performs two functions, namely, that of anchoring the washer against rotation and that of establishing an electrical connection between the contact arm mechanism 45 and the terminal bolt 78.

The operation of my novel current control device is believed to be obvious from the foregoing detailed description. By turning the knob 33 the contact mechanism 45 can be rotated to vary the point of contact between the arm 46 and the resistance 62 of the strip 60. The resilient washer 35 not only provides a universal and resilient mounting for the contact mechanism but also serves to establish an electrical connection between one of the terminal bolts and the contact mechanism. Furthermore, due to the fact that the base 15 is of a molded composition the same may be very economically manufactured.

In Figs. 9, 10, 11 and 12 I have illustrated somewhat diagrammatically a form of resistance strip 60' which may be used in place of the resistance strip 60. This strip 60' comprises essentially an insulator core 61' having wound thereon a resistance wire 62'. This wire 62' is suitably anchored at each end to the core 61'. In this form of strip the core 61' need not be provided with grooves for receiving the individual windings on the strip.

The strip may be wound by any suitable coil winding machine. The resistance wire 62' is preferably provided with insulation such as a coating of black enamel 63'. By using black enameled wire it is possible to wind the strip with the individual turns in contact with each other.

In order to provide a contact surface for the contact arm of the device to engage, I 10 preferably file one edge 64' of the resistance strip 60' to bare the resistance wire 62' of the black enamel insulation 63' at this point. By baring the insulation at 64' I provide a contact surface which extends the length of 15 the strip without at the same time interfering with the insulation between the individual turns of the wire on the strip.

Now I desire it understood, although I have illustrated and described in detail the 20 preferred embodiments of my invention, the invention is not to be thus limited but only insofar defined by the scope and spirit of the appended claims.

I claim:

25 1. In combination, a rheostat base of molded composition having its periphery corrugated, resistance means comprising a core encircling the periphery of the molded base and a resistance element wound upon said 30 core and also encircling said base, the depressed portions of the corrugations opening directly across the periphery of the base to form transverse channels across the periphery of the base from one side of the resistance 35 means to the other and between the resistance element and the molded base for cooling purposes.

2. In an electric current control device, a 40 base of molded composition substantially arcuate in shape and having a corrugated outer periphery resistance means wound about an annular axis encircling the periphery of the molded base and disposed wholly outside the peaks of the corrugations, the depressed portions of the corrugations opening directly 45 across the periphery of the base to form transverse channels across the periphery of the base from one side to the other between the resistance element and the molded base for 50 cooling purposes.

3. In an electric current control device, a 55 base of molded composition having an annular rim and a concave end, a resistance element disposed about said rim, contact mechanism mounted on said end for cooperating with said resistance element, and means for fastening the ends of the element to the rim of the base comprising a plurality of fastening members, said rim having a slot for receiving each of said fastening members and 60 said concave end having a plurality of pockets communicating with the slots in said rim, said pockets receiving portions of said fastening members to lock them against rotation, 65 said contact mechanism including a

spring washer disposed on said depressed end comprising a metallic flange having a lateral extension projecting through an opening in said depressed end into one of said pockets, the fastening member associated with said latter pocket serving to secure said extension to said base to prevent rotation of said washer.

4. In an electric current control device, a 70 base of molded composition comprising a cup having an annular rim, a concave end, and radially extending corrugations normal to said concave end, a resistance element disposed about the said corrugated rim and contact mechanism mounted on said end for cooperating with said resistance element, said mechanism including a spring washer having a lateral arm extending through a slot in said concave end and fastened to said rim.

5. In an electric current control device, a 75 base of molded composition comprising a cup having a corrugated annular rim and a concave end, a resistance element disposed about the peaks of the corrugations in said rim and contact mechanism mounted on said end 80 for cooperating with said resistance element, said mechanism including a spring washer having a lateral arm fastened to said base.

6. In combination, a cylindrical insulating base having its periphery corrugated, and a 90 resistance unit comprising a core encircling the outer peaks of the corrugations with a resistance element mounted upon said core and bridging air passages beneath the resistance unit for cooling purposes.

7. In combination, a cylindrical insulating base having its periphery corrugated, and a resistance unit encircling the periphery of the base and comprising a core having a resistance element wound thereupon, the corrugations in the periphery of the insulating base opening transversely across said base and disposed internally of the inner periphery of said resistance unit for cooling purposes.

8. In an electric current control device of 100 molded composition comprising a cylindrical base member with an external shoulder thereon, the periphery of the base member having corrugations traversing it from one side to the other including the shoulder, a resistance means comprising a core with a resistance element wound thereon disposed about the peaks of the corrugations of the base member having one edge abutting the corrugated shoulder and the other edge overhanging the edge of said base, said corrugations on the base member and shoulder providing a means for air cooling both the windings on the inner periphery of the resistance unit and the 110 windings on the edge abutting the shoulder of said base member.

9. In an electric current control device of 115 molded composition comprising a cylindrical base having transverse ridges across its pe- 120

riphery, said ridges having projections thereon, a resistance means comprising a core with a resistance element wound thereabout supported on said ridges abutting the projections thereon capable of being cooled on all sides by disposition of its outer periphery and one edge thereof to the air and by the disposition of its inner periphery and other edge to the air between the ridges on the cylindrical base.

5 10 In witness whereof, I hereunto subscribe my name this 18th day of October, 1926.

NEWTON C. SCHELLENGER.
